(57) **CLAIM**

The ornamental design for an automobile tire, as shown and described.

DESCRIPTION

FIG. 1 is a perspective view of an automobile tire showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a partially enlarged view of a portion defined by lines 8-8 shown in FIG. 1;

FIG. 9 is a partially enlarged view of a portion defined by lines 9-9 shown in FIG. 8;

FIG. 10 is a partially enlarged view of a portion defined by lines 10-10 shown in FIG. 2; and,

FIG. 11 is a cross sectional view of a portion defined by lines 11-11 shown in FIG. 10.

The broken lines shown illustrate portions of the automobile tire that form no part of the claimed design.
